ADJUSTABLE BILL STOP

Arthur J. Fettig, Detroit, Mich., assignor to Burroughs Adding Machine Company, Detroit, Mich., a corporation of Michigan

Application March 21, 1942, Serial No. 435,692

8 Claims. (Cl. 197—128)

This invention relates to adjustable, retractable paper stop means for business machines, said stop means being adapted to arrest each of a series of papers inserted in the machine in proper position for the printing of data in the desired position on said paper, to thereafter permit said paper to pass out of the machine, and to then arrest the next of said inserted papers in the proper position.

An object of the invention is to provide a retractable paper stop means which is quickly and easily adjustable to position the inserted papers to receive printing impressions at different desired vertical positions thereon.

A further object of the invention is to provide a retractable paper stop means which is adjustable to arrest the inserted papers in different desired positions by easy manipulation of a single member.

A further object of the invention is to provide an adjustable, retractable paper stop means which is of simple and inexpensive construction and reliable in performance of its intended functions.

One embodiment of the invention is illustrated by way of example in the accompanying drawings, in which:

Figure 1 is a right-side elevation of a calculating and accounting machine to which the invention has been applied, with the casing removed but omitting all but those of the principal elements of the machine which will facilitate an understanding of the invention;

Fig. 2 is a fore and aft vertical section through the paper-handling equipment of the machine of Fig. 1, showing some parts of the adjustable paper stop means of the invention;

Fig. 3 is a left-side elevation of portions of the paper-handling equipment of the machine of Fig. 1, illustrating portions of the means for moving the platen from printing position to front-feed position and reversely;

Fig. 4 is a perspective view illustrating the construction and arrangement of the adjustable, retractable paper stop means; and

Fig. 5 is an enlarged detail of Fig. 4.

The invention is shown by way of example as applied to a well-known Burroughs "high keyboard" machine, but it will be apparent to those skilled in the art that the invention is also applicable to various other makes, types and styles of business machines.

GENERAL CONSTRUCTION OF MACHINE

The Burroughs "High Keyboard" machine illus-

trated by way of example is driven by an electric motor 20 through a single-revolution clutch 21 which, together with the electric current supply circuit of the motor, is controlled by the usual control link 22 from a main motor bar M and usually also from one or more additional motor bars and/or function control keys, not illustrated herein. On each elevation of the control link 22, the motor 20, through the clutch 21, drives the shaft 23 and crank 24 through a single revolution to impart to the machine a cycle of operation comprising so-called forward and return strokes. The crank 24, through a link 25, oscillates an arm 26 about the shaft 27 on which it is journaled, clockwise as viewed in Fig. 1 in the forward stroke and counterclockwise in the return stroke of the cycle of operation. In the forward stroke of the cycle, the arm 26 rocks clockwise an arm 28 secured on the shaft 21, whereby an arm 29, also secured on the shaft 21, draws rearwardly a link 30 connected to the usual full-stroke sector 31 secured on the shaft 32, thereby rocking the full-stroke sector 31 and shaft 32 counterclockwise. During the return stroke of the cycle, springs 33, connected between the arm 29 and a fixed member of the machine frame, restore the arm 29, shaft 21 and shaft 32 to normal position, the return stroke being regulated by the usual dash pot, not shown.

Amounts and other data may be entered in the machine by depression of the proper keys in a plurality of banks of keys 40 on the keyboard of the machine prior to a machine cycle. During the amount- or data-entering machine cycle, the usual actuator racks 41 for banks of keys 40 in which keys have been depressed perform excursions downwardly during the forward stroke and return upwardly during the return stroke, the length of the excursion of each moved actuator 41 being determined by that one of the usual stop wires 42 which has been moved to limiting position by depression of the respective one of the keys 40 in the corresponding bank of keys. The actuators 41 are carried by the forward arms of levers 43, the rearward arms of which each carry a series of type which are selectively positioned at the printing line in accordance with the positions at which the actuators 41 are arrested in the forward stroke of the machine cycle, after which, and near the end of the forward stroke, the type at the printing line are driven rearwardly by the usual printing hammers 45 to effect printing impressions. Amounts or other data thus entered in the machine may be also entered in one or more totalizers or registers such as the add and sub-

tract crossfooter 46 or one of a line of adding totalizers or registers 47.

In total-taking and subtotal-taking machine cycles, the actuators 41 are adapted to be controlled in the usual and well-known manner by the pinions of the crossfooter 46 or by the pinions of a selected one of the adding registers 47, whereby said pinions also control the selective positioning of the printing type at the printing line so that the results of calculations performed on the machine are printed.

Front-feed paper equipment

The papers on which printing impressions are to be made are adapted to be supported on a platen roller 60 carried on a platen shaft 61 journaled at its ends in the end plates of a platen frame 62 (Figs. 2 and 3) rockably mounted on a shaft 63 journaled in the end plates of the main paper carriage frame 64. These papers may include a sheet such as a journal sheet J passing around the platen and being permitted to remain in the machine throughout predetermined periods to receive thereon records of all work performed on the machine during such periods, and papers such as bill forms or other work sheets W adapted to be inserted in and removed from the machine in succession for the printing of entries and results on each of said paper successively.

The platen 60 is moved from its printing position to a front-feed position to facilitate the insertion and removal of the papers W and then returned to printing position by rocking the platen frame 62 about the shaft 63. As shown in Figs. 2 and 3, a plate 65 secured to the left-hand end plate of the platen frame 62 is connected to a spring 66 which urges the platen frame in a direction to carry the platen 60 rearwardly away from the printing type 44. The plate 65 also carries a stud 67 engaging the edge of a cam member 68 secured on a shaft 70 journaled in the main carriage frame 64. The shaft 70 has fixed thereon a ball 71, the cross rod of which engages in an open slot in a rearwardly turned projection 72 of a slide 73 which is mounted for up-and-down sliding movements on the rear plate 74 of the machine frame. To the lower end of the slide 73 is secured a plate 75 carrying a stud 76 engaging in a notch in the rear end of a lever 77 pivoted intermediate its ends on the shaft 78 and carrying at its forward end (Fig. 1) a stud 79 engaging in a cam slot in a plate 80 secured on the shaft 27.

The slide 73 is normally in its uppermost position, shown in dot-and-dash lines in Figs. 2 and 3, whereby the cam member 68 is positioned to permit the platen 60 to occupy its rearward or front-feed position. The arrangement is such that, during the forward stroke of a machine cycle, the cam plate 80 rocks the lever 77 clockwise (Fig. 1) to lower the slide 73, thereby rocking the cam member 68 clockwise (Fig. 3) whereby the latter, acting on the stud 67, rocks the platen frame 62 to carry the platen 60 forwardly to printing position relative to the printing type.

The journal sheet J is normally continually pressed against the platen roller 60 in feeding relation therewith by rear pressure rolls 85 (Fig. 3) rotatably mounted on a rod 86 supported at a plurality of points by the upper arms of bell cranks 87 which are adapted to be rocked about a shaft 88 supported in the end plates of the platen frame 62. The shaft 63 has flattened portions 75 between the rearward arms of the bell cranks 87

and the rearward ends of members 89 which are also rockably supported on the shaft 88 and carry at their forward ends springs 90 which extend rearwardly over the shaft 88 and under the rod 86 to urge the rolls 85 to press the journal sheet J against the platen 60. Rotation of the shaft 63 by means of a finger lever to turn the flattened portions of the shaft from a substantially horizontal position to a substantially vertical position will retract the rolls from the platen to permit easy removal of the old and insertion of a new journal sheet about the platen when desired.

When the platen is in its normal rearward or front-feed position, papers W, such as bill forms or the like, may be front fed over a front paper chute 91, which is supported on brackets 92 on the main carriage frame 64, into the open throat between the platen roller 60 and a line of forward pressure rolls 93 rotatable on a rod 94 which is yieldingly supported at the upper front end of a downwardly and rearwardly inclined rear paper table 95 supported between the end plates of the main carriage frame 64. When, during a machine cycle, the platen is rocked forwardly to printing position, it presses the front-fed sheet W and journal sheet against the pressure rolls 93 to grip the papers and support them in printing position prior to the operation of the printing hammers 45. As the platen roller 60 moves forwardly to printing position, the upper portion of the front-fed sheet W is wrapped partially about the platen by the lower edge of the front-feed paper chute 91 thereby facilitating clear, clean printing impressions on the inserted work sheet W. The usual ink ribbon (not shown) is provided for inking the type impressions on the work sheet. The record on the journal sheet is produced by means of a sheet of carbon paper C.

During the return stroke of the machine cycle, counterclockwise rocking of the shaft 27 and cam plate 60 by springs 33 causes the lever 77 to be rocked counterclockwise, thus returning the slide 73 to its upper position and permitting the platen frame 62 to be rocked about the shaft 63 by the spring 66 to return the platen 60 to its rearward, front-feed or open-throat position to permit the front-fed work sheet W upon which entries have been printed to be replaced by the next work sheet on which it is desired to print entries.

The journal sheet J is line-spaced by rotation of the platen 60 by a line-spacing means comprising an arm 100 pivoted on the platen shaft 61 and having pivoted on it a pawl 101 which is urged by a spring 102 into engagement with the teeth of a ratchet wheel 103 fixed on the platen shaft 61. A link 104 is pivotally connected at one end to the arm 100 and at its other end to one of a pair of brackets 105 on the carriage frame 64 so that each time the platen frame is rocked rearwardly to open-throat or front-feed position, the arm 100 is swung about the platen shaft 60 and the pawl 101 rotates the platen 60 to advance the journal sheet.

The brackets 92 on the carriage frame 64 may also support a paper-holding means (Fig. 1) adapted to hold a supply of work sheets, such as bill forms or the like, in position to facilitate the insertion of successive sheets in the front-feed paper throat by the operator.

The paper carriage of the machine, illustrated in the accompanying drawings by way of example, is mounted on the machine for movement laterally on a suitable raceway 110 and is provided with tabulating means comprising a plurality of column stops 111 (Fig. 3) adjustably

secured at desired points along a stop shaft 112 rockably mounted in the main carriage frame 64. The column stop shaft 112 is normally held in a position such that the forward ends of the column stops 111 are positioned to cooperate with a tabulating abutment 113 to hold the carriage in any desired one of the columnar positions corresponding to the positions in which the several column stops 111 have been adjustably secured on the stop shaft 112. The operator may manipulate the manual tabulating lever 114 (Fig. 1) to rock the stop shaft 112 clockwise in Fig. 1 to lift the forward ends of the column stops 111 above the tabulating abutment 113 and then manually move the carriage to the desired columnar position where, upon release of the tabulating lever 114 by the operator, the usual spring 115 returns the parts, including the tabulating stop shaft 112, into position to cause the carriage to be held in the desired columnar position. It should be noted, however, that the adjustable paper stop means of the present invention may be employed also in machines having carriage tabulating mechanisms which operate automatically during successive machine cycles to move the carriage from column to column and also with machines in which the paper carriage frame is fixed on the main machine frame and not movable laterally thereon.

While the platen-rocking or paper throat-opening means illustrated in the accompanying drawings is arranged to cause the platen to be rocked out of printing position and the paper throat to be opened after operation of the printing mechanism in every cycle of operation of the machine, it is to be noted also that the adjustable paper stop means of the present invention described hereinafter are equally well adapted to be used in machines in which the platen-rocking and throat-opening means are arranged and controlled so as to rock the platen out of printing position and open the paper throat after operation of the printing mechanism only in selected machine cycles, such as machine cycles which are performed with the paper carriage in a predetermined columnar position or positions, or cycles of operation performed when the machine is conditioned for a performance of predetermined functions.

Adjustable retractable paper stop means

The paper stop means (Figs. 4 and 5) to arrest the front-fed sheets in proper positions to receive the printed entries at the desired vertical positions on said sheets are supported on a pair of downwardly and rearwardly inclined plates 120R and 120L, each having a pair of downwardly turned lateral lugs 121 (Figs. 2 and 4) with forward projections which engage under the rearward edge of a crossbar 122 of angular section supported in the end plates of the carriage frame 64 just to the rear of the lower rearward edge of the lower paper table 95. The upper front ends of the plates 120R and 120L extend over the upper rear face of the table 95 into close proximity to the front pressure rolls 93. Each plate has, near its lower rear end, a pair of downwardly turned lateral lugs 123 through which a shaft 124 passes, said shaft being secured at its ends in the brackets 105. Collars 125 secured to the lugs 123 have set screws threaded therein to secure the plates 120R and 120L in the desired positions to which they may be adjusted laterally of the carriage.

The adjustable, retractable paper stop means 75

on each of the plates 120R and 120L being identical excepting that the stop means on one plate is the laterally reversed or mirror image of that on the other of said plates, a detailed description of the stop means carried by the plate 120L of Fig. 3 will suffice.

A vertical guide member 130 for the lateral edge of the front-fed sheet W is secured to a bracket member 131 having a pair of laterally turned lugs through each of which passes a screw 132 (only one of which is shown in Fig. 4), each of said screws also passing through an aperture in a plate 133 and being threaded into a respective end portion of a block 134 which is disposed in a longitudinal slot 135 in the plate 120L and also has lateral flanges underlying the plate 120L along the opposite lateral edges of the slot 135, whereby the plate 133, together with the paper guide member 130, may be adjusted longitudinally of the plate 120L to the extent permitted by the length of the slot 135.

The plate 133 is releasably securable in adjusted position longitudinally of the plate 120L by means of a pin 136 (Fig. 5) which passes through an aperture in the upper end of a hollow, cylindrical boss 137 on the slide plate 133 and has, within the enlarged cylindrical bore in said boss, an annular enlargement 138 between which and the upper end wall of said boss 137 a compression spring 139 is confined, whereby the spring 139 urges the pin 136 downwardly through the lower open end of the boss 137. The plate 133 is formed with a plurality of apertures 140 along a line parallel to the edge of the slot 135 and adapted to receive the reduced lower end of the pin 136, whereby the slide plate 133 may be releasably secured in any position of adjustment longitudinally on the plate 120L. A knurled cap nut 141 or the like threaded on an upper, reduced end of the pin 136 may be grasped between the fingers of the operator and drawn upwardly against the tension of the spring 139 to retract the lower end of the pin 136 from that aperture 140 in the plate 133 in which it is currently engaged, after which the plate 133 may be slid to any desired position longitudinally of the plate 120L, also by manipulation of the knurled nut 141, after which the nut 141 is released from the fingers of the operator and the lower end of the pin 136 is projected into another of the apertures 140 in the plate 120L by the spring 139 to secure the plate 133 in its newly adjusted position.

On the upwardly offset upper end of the slide plate 133 there is also an irregularly bent extension 142 having on its end an auxiliary guide 143 for the lateral edge of the front-fed paper.

On a stud 143 secured on the slide plate 133, there is pivoted a bell crank 144, on the end of the upper arm of which is pivoted a paper stop 145 which extends laterally inwardly through the space between the vertical paper guides 130 and 143 into the path of the front-fed papers, said stop member 145 having an extension 146 formed with a slot by which it is guided on a stud 147 secured in an upwardly offset portion of the slide plate 133. The bell crank 144 is urged counterclockwise in Fig. 4 by a spring 148 secured to the lateral arm of the bell crank and to a stud in the slide plate 133.

Between the knurled nut 141 and a shoulder at the lower end of the upper reduced threaded portion of the pin 136 is secured an arm 150 slotted arcuately about the center of the stud 143 to form a pair of fingers 151 (Fig. 5) en-

gaging in an annular groove in the enlarged head of a pin 152 extending through the lateral arm of the bell crank 144 and through a spacing sleeve 153 secured to said bell crank arm and into one of a series of notches 154 formed in the edge of a plate 155 slidably mounted on headed studs 156 (Fig. 4) secured in the plate 133. The slide plate 155 is urged to its normal uppermost position by means of a spring 157 connected between a stud on the slide plate 155 and a stud on the plate 133. It should be noted that, by reason of the construction just described, the lifting of the knurled nut 141 by the operator to disengage the pin 136 from an aperture 140 in the plate 120L also, through the arm 150, lifts the pin 152 to disengage it from the currently engaged notch 154 in the edge of the plate 155, so that the operator by grasping a single piece, the knurled nut 141, may disconnect both of the pins 136 and 152 from both of the plates 120L and 155 and move the plate 133 and stop 145 to any desired position of adjustment where both of the pins 136 and 152 will be re-engaged with the respective plates 120L and 155 upon release of said single piece 141.

It will be apparent also that, by reason of the construction above described, downward and rearward movement of the slide plate 155 will cause the bell crank 144 to be rocked clockwise in Fig. 4 to retract the paper stop 145 from the path of the front-fed sheets. On the slide plate 155 is secured an angular bracket 156, on the upper forward portion of which is pivoted a bell crank 157, the lower arm of which is connected to one end of the spring 158 which is connected at its other end to a lug turned down from one edge of the slide plate 155, whereby the spring 158 normally yieldingly holds the lower arm of the bell crank 157 against an edge of the bracket 156. The forwardly extending arm of the bell crank carries a squared stud 159 adapted to be acted upon by the end of a cam arm 160 secured on a collar 161, in which is threaded a set screw by which the collar 161 and arm 160 may be secured in any desired position on the shaft 70 which, as already described, is rocked clockwise in Figs. 3 and 4 and counterclockwise in Fig. 2 during the forward stroke, and then returned counterclockwise in Figs. 3 and 4 and clockwise in Fig. 2 during the return stroke of each machine cycle.

With the parts in their normal position while the machine is at rest, that is, with the slide 73 in its normal upper position and the platen 60 in its open-throat or front-feed piston, the arms 160, of which there is one for each of the two retractable paper stops 145, are normally positioned as shown in Fig. 3, that is, with their rearward ends below the studs 159, and the two paper stops 145 are positioned as in Fig. 3 in the path of the front-fed paper. At this time the operator may take up a work sheet, such as a billform or the like, from the receptacle 99 and drop it into the front-feed chute 91, whereupon it will be guided into the open throat between the platen 60 and forward pressure rolls 93 and over the upper ends of the plates 120R and 120L. As the front-fed sheet passes through the paper throat, its lower corners will fall against two paper stops 145 which, by reason of the adjusted positions of the slide plates 133, will arrest the front-fed sheet, as shown by the paper W in Fig. 4, in the correct position to receive a printed entry at a desired vertical position thereon.

After entering the appropriate data on the keyboard of the machine, the operator may give the

machine a cycle of operation by depression of the motor bar M whereupon, through the means previously described, the shaft 70 will be rocked clockwise in Figs. 3 and 4 (counterclockwise in Fig. 2) to rock the platen frame 62 and platen 60 to the closed-throat or printing position whereby the front-fed sheet W will be gripped between the platen 60 and the front pressure rolls 93 and held in printing position, with the aid also of the lower edge of the front-feed paper chute. During this movement of the shaft 70 the arms 160 engage the studs 159 and cam the bell cranks 157 counterclockwise in Fig. 4 until the ends of said arms 160 pass the studs 159, whereupon the springs 158 return the bell cranks 157 and studs 159 to their normal positions. Then, near the end of the forward stroke of the cycle the printing mechanism operates to print the appropriate data along the proper line on the front-fed work sheet W.

At the beginning of the return stroke, through the means already described, the shaft 70 is rocked counterclockwise in Figs. 3 and 4 (clockwise in Fig. 2) to permit the platen 60 to rock rearwardly out of printing position to its open-throat or front-feed position. Simultaneously, the ends of the arms 160 act on the studs 159 and, as the bell cranks 157 are prevented from rotating clockwise by reason of the engagement of their lower arms against the edges of the brackets 156, the slides 155 are cammed downwardly and rearwardly and, because of the engagement of the pins 152 in notches in the edges of the slides 155, the bell cranks 144 are rocked to move the paper stops 145 laterally outwardly from beneath the lower corners of the work sheet W as the paper throat opens. The paper on which the printed entry has just been made is thereby permitted to slide downwardly and rearwardly on the plates 120R and 120L between the guides 130 and into a receptacle 165 supported between the brackets 105. It will be noted that the papers enter the receptacle face down and are therefore stacked in the order in which they pass through the machine.

As the shaft 70 completes its movement at the end of the machine cycle the ends of the arms 160 pass the studs 159, thus permitting the slides 155 to be returned upwardly and forwardly to their normal positions by the springs 158 which, with the aid of the springs 148, will project the paper stops 145 again laterally inwardly into the path of the front-fed papers.

It will be noted that the stops 145 are retracted only very briefly and sufficiently to permit the sheet upon which an entry has just been printed to commence its movement downwardly and rearwardly out of the carriage. The facing inner faces of the paper stops 145 are inclined outwardly and upwardly so that, when the stops are returned inwardly toward their normal positions, their leading lower edges will pass under the edges of the sheet passing out of the paper carriage and lift the lateral edges of the sheet above the stops, if the sheet has not already passed beyond the stops. The very brief retraction of the stops and the immediate return thereof into effective position insures that the next work sheet to be dropped into the front-feed throat by the operator will be stopped in the proper position by the stops, no matter how closely the newly inserted paper may follow the paper which is dropping out of the carriage.

It will be apparent that the adjustable retractable stop means as described above are readily

adaptable for use with forms of varying dimensions, and with forms upon which data are to be entered in various vertical and lateral positions. To adjust the mechanism for forms of varying widths and for various columnar rulings on the form, it is only necessary to loosen the set screws in the collars 125 and 161 and to shift the plates 120R and 120L and arms 160 laterally to the appropriate positions on the shafts 124 and 70, where they may be secured by retightening the set screws. To adjust the mechanism for various horizontal rulings on the forms, i. e., to position the forms to receive printed entries in desired vertical positions or lines, it is only necessary for the operator to lift the knurled nuts 141 and, through these same members, shift the slide plates 133 longitudinally of the plates 120R and 120L to place the stops 145 at the desired new vertical positions where the operator may release the knurled nuts 141 to permit the pins 136 and 152 to be re-engaged in the appropriate apertures 140 and notches 154 by the springs 139.

While the form of construction above described is admirably suited for the purposes and functions mentioned, it will be readily apparent to those skilled in the art that the invention may be embodied in various other constructional forms within the scope of the appended claims.

I claim:

1. Adjustable retractable paper stop means for business machines, comprising a support adjacent an edge of the path of papers being passed through the machine, a member mounted on said support adjacent an edge of said path for adjustment thereon along said edge of said path, a paper stop carried on said adjustable member for movement into and out of said path, a stop-moving member movably mounted on said adjustable member, an actuating member movably mounted on said support, means to releasably secure said adjustable member in each of a plurality of positions of adjustment on said support, means to releasably connect said stop-moving member with said actuating member in each of said positions of adjustment of said adjustable member to enable said actuating member by movements thereof on said supporting member to move said stop into and out of said path, and a single manipulative means to operate said securing means and said connecting means and to adjust said adjustable member on said support and re-enable said securing means and connecting means.

2. Adjustable retractable paper stop means for business machines, comprising a support adjacent an edge of the path of papers being passed through the machine, a member mounted on said support adjacent an edge of said path for adjustment thereon along said edge of said path, a paper stop carried on said adjustable member for movement into and out of said path, a stop-moving member movably mounted on said adjustable member, an actuating member movably mounted on said support, means comprising a securing member carried by said adjustable member, to releasably secure said adjustable member in each of a plurality of positions of adjustment on said support, means comprising a connecting member carried by said adjustable member, to releasably connect said stop-moving member with said actuating member in each of said positions of adjustment of said adjustable member to enable said actuating member by movements thereof on said supporting member to move said stop into and out of said path,

and out of said path, and a single manipulative means to operate said securing and connecting members simultaneously and to change the position of securement of said adjustable member on said support and the point of connection between said stop-moving member and said actuating member relative to the latter.

3. Adjustable retractable paper stop means for business machines, comprising a support adjacent an edge of the path of papers being passed through the machine, a stop-supporting member slidably mounted on said support adjacent an edge of said path for adjustment thereon along said edge of said path, a paper stop carried on said slidably mounted member for movement into and out of said path, a stop-moving member movably mounted on said adjustable member, an actuating member mounted on said support for movement in an actuating stroke between fixed points on said slidably mounted member, means carried by said slidably mounted member and engageable with said support to releasably secure said slidably mounted member in each of a plurality of spaced positions of adjustment on said support, means carried by said slidably mounted member and engageable with each of a series of similarly spaced portions of said actuating member to releasably connect said stop-moving member with said actuating member in each of said spaced positions of adjustment of said slidably mounted member to enable said actuating member by movement thereof in its fixed actuating stroke on said supporting member to move said stop into and out of said path, and a single manipulative means to disengage and re-engage said securing means and said connecting means from and with said support and actuating member to adjust said adjustable member on said support between said disengagement and re-engagement.

4. In a machine of the character specified, having driving means, elements forming a paper throat and at least one of which is movable from an open-throat position to a closed-throat position and reversely, and means operated from said driving means for moving said movable element, adjustable retractable paper stop means comprising a support adjacent an edge of the path of papers passing through said throat, a member mounted on said support adjacent an edge of said path for adjustment thereon along said edge of said path, a paper stop carried on said adjustable member for movement into and out of said path, a stop-moving member movably mounted on said adjustable member, an actuating member movably mounted on said support, means to releasably secure said adjustable member in each of a plurality of positions of adjustment on said support, means to releasably connect said stop-moving member with said actuating member in each of said positions of adjustment of said adjustable member to enable said actuating member by movements thereof on said supporting member to move said stop into and out of said path, a single manipulative means to operate said securing means and said connecting means and to adjust said adjustable member on said support and re-enable said securing means and connecting means, and means operable by said moving means as it moves said movable element to open-throat position to move said actuating means to momentarily move said stop out of said path.

5. In a machine of the character specified, having driving means, elements forming a paper throat and including a platen rockable from an open-throat to a closed-throat position and re-

versely, and means operated from said driving means for rocking said platen, adjustable retractable paper stop means comprising a support adjacent an edge of the path of papers passing through said throat, a member mounted on said support adjacent an edge of said path for adjustment thereon along said edge of said path, a paper stop carried on said adjustable member for movement into and out of said path, a stop-moving member movably mounted on said adjustable member, an actuating member movably mounted on said support, means to releasably secure said adjustable member in each of a plurality of positions of adjustment on said support, means to releasably connect said stop-moving member with said actuating member in each of said positions of adjustment of said adjustable member to enable said actuating member by movements thereof on said supporting member to move said stop into and out of said path, a single manipulative means to operate said securing means and said connecting means and to adjust said adjustable member on said support and re-enable said securing means and connecting means, and means operable by said platen-rocking means as it rocks said platen to open-throat position to move said actuating means to momentarily move said stop out of said path and quickly return it into said path.

6. In a machine of the class specified having means to guide papers into the machine in a predetermined path, a pair of movable stop members normally projecting into said path from the opposite lateral edges thereof to stop an inserted paper in a predetermined position in said path, actuating means operated automatically at a predetermined time in the operation of the machine, means operated by said actuating means to move said stops laterally momentarily out of said path to permit said paper to resume movement along said path and to quickly return said stops into said path, and means on said stops to move the lateral edges of said paper transversely to the plane of said paper to permit continuing movement of said paper along said path as said stops are returned into said path in position to stop the following paper.

7. In a machine of the class specified having driving means, elements forming a paper throat and at least one of which is movable from open-throat to closed-throat position and reversely,

means operable by said driving means to move said movable element, a pair of movable stop members normally projecting into the path papers passing through said throat to stop an inserted paper in a predetermined position, means operated by said moving means to move said stops momentarily out of said path to permit said paper to resume movement along said path as said movable element is moved to open-throat position and to quickly return said stops into said path, and means on said stops to move portions of said paper transversely to the plane of said paper to permit continuing movement of said paper along said path as said stops are returned into said path in position to stop the next paper entering said throat while said movable element remains in open-throat position.

8. In a machine of the class specified having driving means, elements forming a paper throat and at least one of which is movable from open-throat to closed-throat position and reversely, means operable by said driving means to move said movable element, a support, a stop-carrying member adjustable to each of a plurality of positions on said support, a paper stop movably supported on said stop/carrying member and normally projecting into the path papers passing through said throat to stop an inserted paper in a predetermined position dependent upon the position of adjustment of said stop-carrying member, stop-moving means on said support, connections between said stop-moving means and said stop adjustable to accommodate adjustments of position of said stop-carrying member, means operable by the means for moving said movable throat-element as the latter is moved to open-throat position, to move said stop momentarily out of said path to permit said paper to resume movement along said path and to quickly return said stop into said path, means on said stop to move a portion of said paper transversely to the plane of said paper to permit continuing movement of said paper along said path as said stop is returned into said path in position to stop the next paper entering said throat while said movable element remains in open-throat position, and a single manipulative means to adjust the position of said stop-carrying member and adjust said connections between said stop and said stop-moving means.

ARTHUR J. FETTIG.
